UNITED STATES PATENT OFFICE.

DAVID F. PETERS, OF ST. PETER, MINNESOTA.

AUTOMOBILE SIGNAL.

Application filed October 21, 1922. Serial No. 596,041.

To all whom it may concern:

Be it known that I, DAVID F. PETERS, a citizen of the United States, residing at St. Peter, in the county of Nicollet and State of Minnesota, have invented certain new and useful Improvements in Automobile Signals, of which the following is a specification.

This invention relates to a signal for 10 automobiles and the like and has for its principal object to provide means for signalling to oncoming vehicles the intention of the driver, thereby preventing accidents and allowing traffic to proceed with assurance and safety.

Another important object of the invention is to provide a signal of this nature that is illuminated and in which the light may be used as a trouble light for the vehicle 20 upon which the signal is mounted.

A still further object of the invention is to provide a signal of this nature which will be efficient and simple in construction, reliable in operation and well adapted to the 25 purpose for which it is designed.

Figure 1 is an elevation of the signal showing the same attached to a portion of the windshield frame.

Figure 2 is a transverse section taken substantially on the line 2—2 of Fig. 1, looking in the direction of the arrow.

Figure 3 is a top plan of the signal.

Figure 4 is a longitudinal vertical section therethrough,

Figure 5 is a perspective of the inner shell of the signal,

Figure 6 is a transverse section through the signal taken substantially on the line 6—6 of Fig. 4 looking in the direction of the 40 arrow, and

Figure 7 is a perspective of the slidable signalling element.

Referring to the drawing in detail it will be seen that the arm of the signal includes 45 an outer shell 1, in which is mounted an inner shell 2, these shells being held together by a screw or other suitable means 3. The outer shell is longer than the inner shell as is clearly indicated in Fig. 4. The inner shell 50 is provided at one end with a closure cap 5 and at its other end with a closure plug 6 having channels extending therethrough for receiving the branches 7 of the electric cord 8, the major portion of which is housed within the inner casing 2. A lug 9 extends from the rear end of the closure plug 6 for a pur-

pose which will be explained later. The closure cap 5 is apertured so as to receive a socket shank 10 which supports an electric bulb 11, which is lighted through the electric cord 8. As will be noted by releasing the screw 3, the outer casing may be removed from the inner casing, and the shank 10 may be removed from the aperture in the closure cap 5, and the bulb 11 may be carried to 60 practically any portion of the vehicle to which the signal is attached, thereby being used as a trouble light. When finished using the bulb 11 as a trouble light, the cord 8 may easily be pushed through the aperture back 65 into the casing 2, and the signal reassembled.

An auxiliary casing 15 is mounted adjacent the end of the outer casing 1 and is provided with a transparent panel 16 having written thereon the word "Slow". This auxiliary casing 15 communicates with the outer casing 1 so that the light therein will illuminate the auxiliary casing also. The outer casing is provided with an aperture 17 70 and has slidably mounted within itself, and adjacent the aperture 17, a transparent signal element 18 having printed thereon the letters "L" and "R" in spaced relation to each other, and the signal element is provided 75 with an aperture 19 engageable by the hooked end of the slidable rod 20 which is carried in the bracket 21 on the outer casing 1, being readily operated from the driver's seat of the automobile. This signal element 80 forms a direction indicator which will show from the front and rear of the vehicle, there being two of the apertures 17 as indicated to advantage in Fig. 6, and it is also to be noted in the same figure that there are two 85 panels 16 in the auxiliary casing 15. A panel 16 in the auxiliary casing 15. A spring 23, is positioned in the auxiliary casing and bears against the end of the rod 20 90 therein so as to hold its hooked end in the aperture 19 of the signal element 18. An arrow-head of suitable construction indicated at 24 is mounted on an extension 25 which is screwed to the end of the outer casing 1 or otherwise held in engagement therewith.

A fulcrum bracket 25 is clamped to a rod 26 which in turn is clamped to the frame of the windshield. A clamp bracket 27 is disposed above the outer casing and pivoted to the fulcrum bracket 25, a cylinder 28 is 100 formed integral with the fulcrum bracket 25, and has a coil spring therein as is indi- 105 110

cated in dotted lines in Fig. 1, and the plunger 29 rides in this cylinder thereby forming a buffer for the signal arm. A spring 30 is attached to the clamp member 27 and also the end of the rod 26. This end of the rod 26 terminates in a yoke shaped pocket 31, for receiving the arm when in a vertical or non-signalling position as indicated to advantage in Fig. 1 by the dotted line structure. An operating rod 32 is connected to the clamp member 27 so that the arm may be pivoted as desired. A standard 33 extends from the rod 26 terminating in a yoke shaped piece for receiving the arms when in a horizontal or signalling position. A standard 34 is clamped to the rod 26 and has pivoted at its upper end, a catch 35 for engaging the projection 9 and this catch is spring pressed by a spring 36. A rod 37 is attached to the catch so that it may be readily operated for releasing the lug 9. A mirror of any preferred construction is preferably attached to the clamp member 27 as is shown at 38.

It is thought that the operation and construction of the invention will now be readily understood it being seen that the device is convenient in its operation and tends to greatly facilitate the operation of a motor vehicle in traffic, and at the same time is useful when this motor vehicle has trouble at night where illumination is necessary for making repairs and the like.

Having thus described my invention, what I claim is:—

- 35 1. In combination, a bracket having a pair of rest members associated herewith, a signal arm fulcrumed on the bracket, and engageable with one rest member when in a vertical position and with the other rest member when in a horizontal position, a buffer device associated with the rest member for engaging the arm as it is moved to a horizontal position, a spring for normally holding the arm in a vertical position, means for fulcruming the arm, and a catch for holding the arm in a horizontal position.
- 40 45 2. A signal arm of the class described in-

cluding an outer casing, an inner casing within the outer casing, an electric cord housed within the inner casing, an electric socket connected to the cord and removably mounted in the end of the inner casing, and a signal element slidably mounted in the outer casing so as to be associated with said electric socket when mounted in said inner casing.

3. A signal arm of the class described including a casing having an aperture therein, a source of illumination associated with the aperture, a transparent slideable signalling element associated within the casing adjacent the aperture, and means for sliding the signal element.

4. A signal arm of the class described including an elongated casing having an aperture adjacent the end thereof, a signal slideable within the casing adjacent the aperture, a rod having a hooked end engageable with the signal for sliding the same, and a spring for holding the hooked end of the rod in engagement with the signal.

5. In combination, a signal arm including an elongated casing, an auxiliary casing attached to the elongated casing and communicating therewith, a transparent panel in the auxiliary casing, said elongated casing provided with an aperture adjacent the auxiliary casing, a source of illumination in the elongated casing adjacent the aperture, a transparent signal element slideable in the elongated casing adjacent the aperture, a spring in the auxiliary casing, a rod having a hooked end engageable with the transparent signal element, said spring adapted to engage the hooked end of the rod for holding it in engagement with the transparent signal element.

In testimony whereof I affix my signature in presence of two witnesses.

DAVID F. PETERS.
